Primary Examiner — Jennifer L Rempfer*Assistant Examiner* — Salamah Jordan(74) *Attorney, Agent, or Firm* — Suzanne Kikel**CLAIM**

The ornamental design for an accessory for a weight, as shown and described.

DESCRIPTION

FIG. 1 is a left side perspective view of an accessory for a weight in an open configuration and positioned around the weight, showing my new design;

FIG. 2 is a left side elevation view of FIG. 1;

FIG. 3 is a left side perspective view of the accessory for a weight in a close configuration and positioned around the weight;

FIG. 4 is a front elevation view of FIG. 3;

FIG. 5 is an enlarged left side elevation view of the accessory for a weight in a close configuration without a weight;

FIG. 6 is a right side elevation view thereof;

FIG. 7 is a left side elevation view thereof;

FIG. 8 is a rear elevation view thereof;

FIG. 9 is a front elevation view thereof;

FIG. 10 is a top plan view thereof; and,

FIG. 11 is a bottom plan view thereof.

The broken lines in the drawings are for illustrative purposes and form no part of the claimed design.
